UNITED STATES PATENT OFFICE.

GEORGE E. NORRIS, OF COLUMBUS, OHIO.

VENDING MACHINE.

Application filed September 4, 1923. Serial No. 660,666.

To all whom it may concern:

Be it known that I, GEORGE E. NORRIS, a citizen of the United States, residing at Columbus, in the county of Franklin and 5 State of Ohio, have invented certain new and useful Improvements in Vending Machines, of which the following is a specification.

The present invention is directed to improvements in vending machines of the coin control type.

The primary object of the invention is to provide a vending machine so constructed that upon the insertion of a coin the mechanism will operate to deliver different quantities of merchandise, such as ball gum or peanuts or the like. For instance, if a person inserts a coin in the machine and the mechanism is set to deliver one quantity, 20 such quantity will be delivered and the mechanism will then be set for an increased amount of merchandise up to a predetermined quantity, after which the mechanism will be set to repeat the measured quantity 25 of merchandise.

With these and other objects in view, as will appear as the description proceeds, the invention consists in the novel features of construction, combinations of elements and 30 arrangements of parts, and hereinafter to be fully described and pointed out in the appended claims.

In the accompanying drawing:

Figure 1 is a side elevation of a vending 35 machine with parts broken away to more clearly illustrate the coin control mechanism,

Figure 2 is a horizontal sectional view taken through the machine, and illustrating 40 the coin control mechanism, and

Figure 3 is a sectional view on the line 3—3 of Figure 2.

Referring to the drawing 1 designates the casing of the vending machine having 45 mounted therein the rotatably supported merchandise carrier 2 which is the same construction as that shown in my Patent No. 1,464,682 August 14, 1923. This carrier is provided with a circular series of perforations 3 adapted to be engaged by the teeth of the star wheel 4, said wheel being fixed to the inner end of the operating shaft 5 which is journaled in the bearings 6 supported in any suitable manner by the walls 50 7 which is secured to the casing 1.

Fixed to the shaft 5 is a main wheel 8

having its periphery formed with a plurality of ratchet teeth 9 and circumferentially spaced stops 10, 11, 12 and 14 and a shoulder 13, the purpose of which will appear later.

A spring pressed pawl 15 is pivotally connected at one end to the wall 7 and has a lateral arm 16 which operates in a slot 16' in said wall, said arm having a curved finger 18 adapted to engage the periphery of the wheel 8, in a manner to later appear. This pawl has its free end provided with an offset lug 17 adapted to co-operate with the wheel 18' which is rotatably supported on 65 the wall 7, said wheel having teeth 19. This wheel is provided with a plurality of spaced webs 20, 21 and 22 and resultant slot 23, 24 and 25 with which the offset lug 17 successively engages.

A spring pressed dog 26 is pivotally supported on the wall 7 and is adapted to engage the ratchet teeth 9, shoulder 13 and stops 11 and 12 to prevent reverse or backward rotation of the shaft 5 after the initial 70 movement thereof in a clockwise direction. The shaft 5 is provided near its inner end with a tooth 27 which is adapted to engage the teeth 19 of the wheel 18' to impart step by step rotary movement thereto in an anti-clockwise direction when the shaft 5 is rotated through the medium of the knob 28.

A coin slot 29 is provided to permit a coin 75 30 to be dropped so as to settle upon the shaft 5 and between the arm 16 and a lateral finger 31 carried by the wheel 8.

It will be obvious that when the coin 30 is located between the finger 31 and arm 16 and the shaft 5 is rotated to the right the coin will cause the finger 18 to be raised so as to clear the stop 10 and simultaneously lift the lug 17 from engagement in the slot 25 and clear the web 20, which will permit the wheel 18' to rotate under the action of the tooth 27 a distance sufficient to permit the lug 17 to drop into the slot 23. After the lug 17 is engaged in the slot 23 the finger 18 will drop and will ride upon the periphery of the wheel 8, the rotation of the wheel 8 being arrested when the finger engages the stop 10. As the shaft 5 is rotated the wheel 4 will rotate the carrier 2 so as to discharge a measured quantity of merchandise which may be in the form of ball gum or peanuts or the like.

Since the webs vary in length it will be apparent that when the next coin is inserted

the lug 17 will be raised and will ride on the web 21 and will ride thereon until the shaft 5 makes two revolutions, thus stepping the wheel 4 two teeth, after which the 5 lug 17 will engage the succeeding slot 24 so as to again permit the finger 18 to ride upon the periphery of the wheel 8. It will be of course apparent that when the shaft 5 and wheel 8 make two revolutions the carrier 2 10 will be rotated so as to deliver two balls of gum or two quantities of other merchandise. Since the webs 22 are of greater length than the other webs it will be obvious that the lug 17 will be held out of engagement with the 15 succeeding slot 25 for a longer interval thus permitting the shaft 5 to make three complete revolutions, after which the operation will again be repeated. By varying the length of the respective webs a number of 20 combinations may be obtained.

What is claimed is:

1. In a vending machine, a coin controlled mechanism comprising a shaft, a wheel rotatable with the shaft, a second wheel having webs of varying lengths thereon, a pawl, a coin chute capable of depositing a coin for engagement with the pawl, said pawl having a lug for successively engaging said webs to hold the pawl in an inactive position to 25 permit the shaft to be rotated a predetermined number of times.
2. In a vending machine, a coin controlled operating mechanism including a shaft, a wheel fixed to the shaft and rotatable there- 30

with, a second wheel having webs of varying lengths thereon, a pawl pivotally associated with the wheels, a coin chute capable of depositing a coin for engagement with the pawl, said pawl having a lug for successively engaging said webs to hold the same in an 40 inactive position to permit the shaft to be rotated a predetermined number of times, and means carried by the pawl for limiting the rotation of the first named wheel in one 45 direction.

3. In a vending machine, a coin controlled operating mechanism including a shaft, a wheel rotatable with the shaft, a second wheel, a pawl, a coin chute capable of depositing a coin for engagement with the first 50 named wheel and pawl to elevate the latter when the shaft is rotated, and means on the second wheel for varying the length of time the pawl is elevated when the shaft is rotated.

4. In a vending machine, a coin controlled mechanism including a shaft, a wheel fixed to the shaft having a finger thereon, a pawl, a second wheel having webs of varying length thereon, a coin chute for depositing a coin between the finger and pawl to raise the latter when the shaft is rotated in one direction, said pawl being capable of selectively engaging the webs to hold the pawl elevated to 55 permit the shaft to rotate for a predetermined number of times.

In testimony whereof I affix my signature.

GEORGE E. NORRIS.
